(57) **CLAIM**

The ornamental design for a garment, as shown and described.

DESCRIPTION

FIG. 1 is a front perspective view of a garment in accordance with a preferred embodiment of our design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.

The broken lines in the figures shown as alternating long dashes and short dashes are for the purpose of showing a dress form and indicia that form no part of the claimed design. The even dashed lines represent stitching, and are part of the claimed design.
